UNITED STATES PATENT OFFICE.

FRED HIMMEL AND ISIDORE HIMMEL, OF NEW HAVEN, CONNECTICUT, ASSIGNORS TO THE HIMMEL BROTHERS CO., OF NEW HAVEN, CONNECTICUT, A CORPORATION.

DESIGN FOR A STORE-FRONT CONSTRUCTION STRIP.

Application filed October 24, 1928. Serial No. 28,616. Term of patent 14 years.

To all whom it may concern:

Be it known that we, FRED HIMMEL and ISIDORE HIMMEL, citizens of the United States, residing at New Haven, in the county of New Haven and State of Connecticut, have invented a new, original, and ornamental Design for a Store-Front Construction Strip, of which the following is a specification, reference being had to the accompanying drawing, forming part thereof.

Fig. 1 is a face view of a portion of a store front construction strip showing our new design; and

Fig. 2 is a sectional view on the line 2—2 of Fig. 1.

We claim:

The ornamental design for a store front construction strip as shown.

FRED HIMMEL.
ISIDORE HIMMEL.
